UNITED STATES PATENT OFFICE.

FREDERICK J. HOYT, OF CHICAGO, ILLINOIS.

AMALGAMATING-MACHINE.

SPECIFICATION forming part of Letters Patent No. 770,290, dated September 20, 1904.

Application filed April 22, 1903. Serial No. 153,801. (No model.)

To all whom it may concern:

Be it known that I, FREDERICK J. HOYT, a citizen of the United States, residing at Chicago, in the county of Cook and State of Illinois, have invented certain new and useful Improvements in Amalgamating-Machines, which are fully set forth in the following specification, reference being had to the accompanying drawings, forming a part hereof, and in which—

Figure 1 shows my said new amalgamating-machine in central vertical section. Fig. 2 shows a modified form of its construction. Fig. 3 shows a spherical member thereof, separated and in section on a plane turned a quarter-way round from that shown in the two preceding figures.

Like reference-letters denote like parts throughout.

The object of my invention is to produce a more efficient machine for dry amalgamation than is now obtainable. To attain said desired end, I construct my said new machine in substantially the following manner, namely:

I provide a tank or holder A, having an interiorly-concaved bottom, in the axial center of which is a pipe *m*, a foot or more in length, extending equally inward and outward, screw-threaded interiorly at said inner end, and exteriorly threaded and provided with a cap *k* at its outer end, and into said inner end is screwed the tubular stem *l* of a hemispherical bowl *i*, and into said bowl is floated a cast-iron globular hollow shell D, incased in a copper shell *e*, which is preferably silvered and amalgamated. Screw-threaded equatorially-placed couplings D' connect the hemispheres of said globe, and polarly thereto are axle-stubs *b*, mounted in ball-bearing boxes (indicated in broken outlines in Figs. 1 and 2) so placed as to or nearly to semisubmerge said globe in mercury *h*, held in said bowl *i* and its stems *l* and *m*. As the primary object of said axle ends and bearings is merely to hold said floated ball axially in line with the axis of the tubes *l* *m* and to revolve it with the least possible friction, said globe is either

made of such specific gravity to quicksilver as will coincident the axes of said polar stubs and their bearings. When too light, the globe 50 may be ballasted with quicksilver to the desired specific gravity. The diameter of said globe may be two feet, the thickness of the mercury film *h* one inch each, more or less, and the height of the holder A four or five feet. 55

Into the top of the holder A is set a conical funnel C, supported by a flange on a flange of said holder and bolted thereto. Said funnel has a crooked discharging-spout *g*, which throws its charge on one side of the vertical axis of the globe, which by its impact and the weight thereof causes the ball to revolve, or, more accurately, roll in its supporting medium, whereby said load will be discharged onto said medium, which arrests and washes 65 away the sand and debris adherent to the ball after it has become slightly submerged, is released, and rises and moves outward to the brim of the bowl, from which it is lifted and precipitated and passes through the openings 70 *n* of the holder; but the gold is retained, sinks, and is removed with the cap *k*. A fan E sends a current of air through a pipe B, whereof its nozzle *f* is placed near the entrance of the funnel-spout *g*, which thereby 75 forces the dry sand, powdered rock, and the like supplied to the funnel through the nozzle *g*, which through such impact and the weight of such material revolves the globe.

In the modified form of this amalgamator 80 the funnel C is omitted and a hopper O, at the fan or at any convenient place along the pipe B, receives and sends the material through said pipe to the globe D. The advantage gained by said modification is a thorough dis- 85 integration of the material before it reaches the amalgamating-ball D, and thereby does its work more effectually.

In Fig. 3 the end of the spout *g* is shown on its longitudinal side. Its discharging end 90 is concentric with the ball.

What I claim is—

1. The combination with an air-tube having an air-mover at one end and a nozzle at its

other end, and a funnel under said nozzle of a bowl and a globe in said bowl semisubmerged in mercury.

2. The combination with an air-tube having 5 an air-mover at one end and a nozzle at its other end and a funnel under said nozzle of a bowl and a globe in said bowl semisubmerged

in mercury, and a casing around said globe supporting said funnel.

FREDERICK J. HOYT.
